UNITED STATES PATENT OFFICE.

WILHELM HENNING AND FRANZ GADEKE, OF HAMBURG, GERMANY.

ICE APPARATUS.

Application filed May 18, 1927, Serial No. 192,436, and in Germany September 1, 1926.

The invention is directed to a refrigerating apparatus in which refrigeration is produced by the reaction of suitable chemicals.

The primary object of the present invention is the provision of an apparatus of this type constructed to be conveniently portable and including a casing in which is secured an insulating receptacle open at both ends. A material receiving tank is adapted to be removably inserted within the insulating receptacle from one end of the latter and removably sealed in its connection with such insulating receptacle. The casing, which includes the remaining open end of the insulating receptacle, is adapted to receive a cap carrying means for closing the adjacent end of the insulating receptacle.

A further object of the invention is the provision in the material tank of means for directing the cooling effect to the center of the material being chilled or frozen, with such material tank exteriorly formed to increase conduction, with the said conduction increasing means serving to maintain agitation and therefore proper mixture of the freezing chemicals during the use of the apparatus.

The invention is illustrated in the accompanying drawings, in which:

Figure 1 is a vertical sectional view through a refrigerating apparatus constructed in accordance with the present invention.

Figure 2 is a transverse section on the line A—B of Figure 1.

A casing *a* open at both ends is formed near one end, hereinafter termed the upper end, with an inset portion providing a shoulder *a'* above which the wall of the receptacle is appropriately bent to receive and secure a ring *i* which is interiorly threaded. An insulating receptacle in the form of a double walled glass body *s* is arranged within the casing *a*, the lower end of the insulating receptacle being of reduced diameter to engage a flange *s'* inturned at the lower end of the casing *a*. The insulating receptacle extends below the lower end of the casing and is, it will be noted, open at both ends.

The material tank *c* is shown of conical form with an out-turned edge flange *c'* which overlies and rests upon the upper end of the insulating receptacle, a suitable packing ring *c''* being interposed between the parts. A clamping ring *p* is threaded within the ring *i* and bears upon the flange *c'* of the material tank, thus serving, through the use of the

packing ring *c''*, to cause the material tank to seal the upper end of the insulating receptacle.

The material tank, which as stated is preferably of conical form, is exteriorly provided with additional heat transference means which, in the form shown, is a spirally arranged web *d* which extends from the upper edge of the tank to the bottom. This web not only assists in transferring heat in the well known manner but also serves as an agitator and mixer for the chemical solution, as will be later described. The web may, if desired, be formed with openings *r* extending therethrough.

A lifting element is adapted to be inserted in the material tank, such element being in the form of a tubular member *u* extending axially of the tank and having radiating vanes *v*. In the event the material in the tank is to be frozen solid, it will, of course, adhere to the vanes and may be lifted from the tank in the lifting of the element. Furthermore, the vanes and central tube tend to a more ready transference of heat on the central portion of the material and hence to a more rapid freezing of the material. The upper end of the lifter is provided with a link for convenience in lifting the material from the tank.

The upper end of the tank is closed by a block *g* recessed at *g'* to accommodate the link *w* and bearing on the flange *c'* of the tank and against the block *p* by an interposed gasket *g''*. A yoke *k* overlies the upper portion of the apparatus, having terminal hooks *k'* to engage beneath the shoulder *a'* of the casing, this yoke having a transverse upper bar *k''* centrally treaded at *k'''* to receive the threaded stem *l* of a thumb-screw having a foot *y* seating in a recess in the cover block *g*. Obviously, the block may be sealed in position by pressure of the thumb-screw or the pressure of the thumb-screw relieved and the cover block *g* removed. The foot *y* of the thumb-screw is adapted to engage the link *w* after removal of the cover plate, so as to permit the lifter and accumulated material to be moved upwardly in the material tank to facilitate its removal.

A cap *f* is designed to close the lower end of the casing *a*, serving to seal such lower end. This cap *f* is provided with a plug *f'* adapted to enter and seal the lower end of the insulating receptacle.

- After the introduction of the material to be frozen into the material tank and the sealing of the latter in place, appropriate chemicals are introduced within the lower end of the insulating receptacle and the cap *f* applied. The receptacle is then subjected to more or less agitation by reversing it end for end to cause the chemicals to flow lengthwise the material tank. In this movement it is of course apparent that the web *d* assists in maintaining proper agitation and mixture of the chemicals and thereby facilitates the heat absorbing function. The cover *t* may fit over the upper end of the apparatus if desired and the cap *f* may have graduations *o* to permit the cap to serve as a measure for the chemicals to be introduced. A relief opening closed by a plug *e* may be formed in the cover plate *g* if desired.
20. What is claimed to be new is:
1. A refrigerating apparatus including an insulating receptacle open at both ends, a material receiving tank arranged within the receptacle and adapted to seal one end thereof, and means for removably sealing the opposite end of the insulating receptacle to provide a closed space in said receptacle exteriorly of the material tank for the reception of the refrigerating chemicals.
  2. A refrigerating apparatus comprising a casing, an insulating receptacle open at both ends and arranged within and spaced from the walls of the casing, a material receiving tank arranged within the receptacle and adapted to seal one end thereof, and a cap removably engaging the casing and sealing the opposite end of the receptacle.
  3. A refrigerating apparatus comprising a casing, an insulating receptacle open at both ends and arranged within and spaced from the walls of the casing, a material receiving tank arranged within the receptacle and adapted to seal one end thereof, a cap removably engaging the casing and sealing the opposite end of the receptacle, and a heat trans-

ference web arranged exteriorly of the material receiving tank.

4. A refrigerating apparatus including an insulating receptacle open at both ends, a conical material receiving tank arranged within the receptacle and adapted to seal one end thereof, and means for removably sealing the opposite end of the insulating receptacle to provide a closed space in said receptacle exteriorly of the material tank for the reception of the refrigerating chemicals.

5. A refrigerating apparatus including an insulating receptacle open at both ends, a conical material receiving tank arranged within the receptacle and adapted to seal one end thereof, means for removably sealing the opposite end of the insulating receptacle to provide a closed space in said receptacle exteriorly of the material tank for the reception of the refrigerating chemicals, and a material lifter arranged within the material tank and comprising a central element and vanes radiating therefrom.

6. A refrigerating apparatus including a metallic casing, a double walled glass receptacle open at both ends arranged within the casing, a conical metallic material tank having a flange to overlie the upper end of the glass receptacle to seal the latter at one end, a cap removably cooperating with the casing, a plug carried by the cap to seal the opposite end of the glass receptacle, a threaded ring carried by the upper end of the casing, a pressure element having threaded cooperation with the ring and bearing upon the flange of the material tank, a yoke removably engaging the casing, a cover block arranged to overlie the upper end of the tank, and a member threaded through the yoke and bearing on the block to seal the tank.

In testimony whereof they affix their signatures.

WILHELM HENNING.
FRANZ GADEKE.
